UNITED STATES PATENT OFFICE.

JAMES MARSHALL STRACHAN, OF NORTH ACTON, LONDON, ENGLAND.

SLIDING WINDOW OF MOTOR AND OTHER VEHICLES.

Application filed July 5, 1924, Serial No. 724,431, and in Great Britain August 28, 1923.

This invention relates to the windows of omnibuses and other like vehicles and has for its object to provide a simple and efficient means of counterbalancing such windows that can be adjusted to suit the weight of different windows and to compensate for the loss of energy in the counterbalancing means, also to provide a simple and efficient means of maintaining the window in the position to which it has been raised or lowered and of releasing the same.

The present invention consists in providing the window frame with one or more spring operated windlasses upon which are wound cords or equivalent parts whose outer ends are secured to the sash guides, in providing the edges of the window frame that travel in the guides with parallel plates that are normally urged apart and means for moving the said plates towards each other when it is desired to lower the window.

According to one mode of carrying my invention into practice I provide the lower horizontal member of the window frame with a recess between its faces that extends upwards for a sufficient distance from its lower edge to accommodate a windlass comprising a drum mounted freely on an arbor journaled between two plates maintained at a suitable distance apart. One end of a wound spring is connected to the aforesaid drum and the other to the arbor which is provided with means of turning it with or without a key for the purpose of adjusting the tension of the spring. Means such as a ratchet and pawl are also provided to maintain said arbor in the adjusted position.

One end of each of two cords are secured to the drum and the other ends are led along channels in the lower and side edges of the window and around guide pulleys to the sash guides on opposite sides of the window to which they are secured and the tension on the spring is adjusted to as nearly as possible counterbalance the window.

To the corners formed by the vertical sides and the front and back faces of the window frame I apply angle plates. One of each pair of these angle plates on each side of the window is secured to the window frame and the other is linked to its fellow in such a way as to insure their parallelism in all positions and to cause the distance between them to be increased when the movable member is raised or the other one lowered so as to normally cause the window to bind in the sash

guides. In order to urge these plates away from each other the movable one is normally raised by a spring while gravity tends to move the other in the opposite direction. 60

With this arrangement the angle plates are moved sufficiently nearer to each other when the window frame is raised to allow it to slide in its guides but in order to lower the window the movable plate must be first lowered. For this purpose a horizontal shaft is mounted in bearings in a groove at the top of the window frame and is provided with a lever adjacent to the finger or lifting plate by means of which the window can be 70 raised or lowered. This shaft is also provided with short arms at its extremities whose ends are connected to the movable plates by links or equivalent means in such a way that the said plates are lowered when the aforesaid lever is moved towards the lifting plate when the latter is grasped for the purpose of raising or lowering the window.

I will now proceed to more particularly describe my invention with the aid of the 80 accompanying drawings in which—

Fig. 1 is a front elevation of the door of a vehicle viewed from the inside, to the window of which the present improvements have been applied, 85

Fig. 2 is a front elevation of the window frame shown in Fig. 1 and its guides removed from the door,

Fig. 3 is a horizontal section through the door shown in Fig. 1, in the plane indicated 90 by the broken line 3—3 in that figure,

Fig. 4 is a side elevation of the window frame removed from its guides,

Fig. 5 is a side elevation of the parallel angle-plates detached from the window-frame and viewed from the inside, 95

Fig. 6 is a vertical section through the door shown in Fig. 1 with the window removed, showing one of the removable guides and the end of one of the flexible cords of 100 the counterbalancing mechanism and

Fig. 7 is a vertical section through part of the window frame of a door illustrating a modified construction hereinafter referred to, 105

According to the construction shown in the drawings the window-frame *a* is provided with angle-plates *b* *c* at each of the corners formed by the intersection of its vertical sides, with its back and front faces. 110 The angle-plates *b* are respectively secured to the rear corner on each side of the win-

dow frame by screws *d* and each of the angle-plates *c* is connected to its fellow angle-plate *b* by parallel links *e* pivoted to both of them. The angle-plates on each side 5 of the window-frame are normally urged apart by a spring (not shown) contained in the tube *f* pivoted to a lug *g* on the angle-plate *b*. This spring acts on a plunger *h* that engages a lug *i* on the other angle-plate 10 *c* causing it to move away from the angle-plate *b*.

The angle-plates *b* *c* on both sides of the window frame are adapted to slide in guides *j* when free to do so. Each of these guides 15 is removably supported in the window opening of the door *k* by a screw *l* which enables the lower ends to be moved towards the outer ledge when the window is closed.

In order to facilitate the closing of the 20 window, spring-operated windlasses are supported in recesses formed between the faces of the window frame *a*. Each of these windlasses comprises a hollow drum *m* mounted rotatably on a pivot *n* journalled 25 between plates *o* whose outer surfaces are flush with the window-frame. The opposite ends of wound springs (not shown) are respectively connected to each drum and its pivot which may be rotated to adjust the 30 tension on its spring and such adjustment is maintained by a ratchet wheel *p* and a pawl *q* pivoted to one of the plates *o*. The ends of flexible cords *r* are respectively secured to each of the guides *j* and to the periphery 35 of the adjacent drums *m* whose springs tend to wind them up and so partly counter-balance the window. To facilitate the attachment of the cords *r* to the guides the latter are provided with key-hole slots *s* to receive a flat-head *t* formed on the horizontal 40 member of an L-shaped part secured to one end of each cord.

In fitting the improved window to the 45 door, the beadings *u* *v* are removed and the lower end of the window frame *a* with its guides *j* in position, as shown in Fig. 2, is inserted into its housing to facilitate which one side of the groove *w* on each side 50 of the window is chamfered as is shown at *x*. The guides are next secured by the screws *l* and the beadings *u* *v* are finally restored to the positions shown in the drawings.

In order to raise or lower the window it 55 is necessary to release the grip on the guides by lowering the angle-plate *c* for which purpose a spring-controlled horizontal shaft *y* is mounted in bearings *z* in a groove 1 at the top of the window-frame *a*. This shaft is provided with short arms *2* at both ends 60 that extend into transverse grooves *3* formed in the said angle-plates in order that longitudinal movement may be imparted to them when the shaft *y* is turned. The shaft *y* is also provided with a third arm *4* at or near 65 its centre above a lifting plate *5*. This arm

has a plate *6* at its extremity and is situated in a convenient position to be operated by the thumb when the window is raised or lowered.

The window frame is provided with a 70 downwardly turned lip *7* adapted to engage the knife edge *8* fixed to the outer ledge of the window opening when the window is closed so as to exclude rain and draught.

Springs *9* are provided to normally urge 75 the lower ends of the guides *j* and the window away from the knife edge *8* to enable the latter to be lowered when desired.

According to an alternative construction 80 the guides *j* fit the groove *w* in the window opening which prevents them from swinging and in order to exclude rain and draught when the window is closed it is provided with a strip *10* of rubber or other yielding 85 impervious material having an inclined surface that is brought into contact with a knife edge *11* when the window is closed.

I claim:

1. An improved sliding window for motor and other vehicles comprising a window sash and adjustable counterbalancing means constituted by one or more windlasses each consisting of a frame secured to the window sash; a pivot in said frame on which a drum is journalled; a wound spring surrounding said pivot and connected to it at one end and to the drum at the other; flexible members secured at one end to said drum or drums around which such flexible members are wound and secured at their other extremities to the window guide on each side of the window; means of turning the drum pivot in one direction to adjust the tension of its spring and a ratchet-wheel mounted on said pivot adapted to cooperate with a pawl to prevent its rotation in the reverse direction substantially as and for the purpose set forth. 95 100 105

2. An improved sliding window for motors and other vehicles according to claim 1 having expandible edges adapted to grip the window guides to maintain the window in an adjusted position and to slide therein when contracted also means of contracting said edges substantially as set forth. 110

3. An improved sliding window for motors and other vehicles according to claim 1 having expandible edges each of which comprises two angle-plates, one of which is secured to the window frame and the other connected to the fixed one by links pivoted to each, a spring to urge the angle-plates apart and hand-operated means to urge them together substantially as and for the purpose set forth. 115 120 125

4. An improved sliding window for motors and other vehicles according to claim 1 having expandible edges, each of which comprises two angle-plates, one of which is secured to the window-frame and the other 130

connected to the fixed one by links pivoted to each, a spring to urge the angle-plates apart, means for urging the movable angle-plate towards the fixed one so as to contract the edge of the window-frame comprising a horizontal shaft having arms at its extremities adapted to engage slots in said movable angle-plates and another arm adapted to turn said shaft in the direction to contract the edges of the window substantially as set forth.

5. An improved sliding window for motors and other vehicles according to claim 1 having expandible edges removable guides 15 in which said expandible edges are adapted to slide and means of securing said guides within the window opening so as to enable a lip at the lower edge of the window to engage and be disengaged from a knife-edge fixed to the window ledge substantially as described in the specification.

6. An improved sliding window for motor and other vehicles comprising a window sash and adjustable counterbalancing 25 means constituted by one or more windlasses each consisting of a frame secured to the window sash; a pivot in said frame on

which a drum is journalled; a wound spring surrounding said pivot and connected to it at one end and to the drum at the other; 30 flexible members secured at one end to said drum or drums around which such flexible members are wound and secured at their other extremities to the window guide on each side of the window; means of turning the drum pivot in one direction to adjust the tension of its spring; a ratchet-wheel mounted on said pivot adapted to co-operate with a pawl to prevent its rotation in the reverse direction; removable window 40 guides adapted to fit grooves in the window opening in which they are held stationary by removable beadings; a strip of impervious elastic material near the lower edge of the window; an inclined surface to said strip 45 and an edge near the bottom of the window opening engaged by said strip when the window is closed to exclude rain and draught substantially as set forth.

In testimony whereof, I have signed my 50 name to this specification at 18 Cavendish Square, London, England, this 5th day of June, 1924.

JAMES MARSHALL STRACHAN.
